UNITED STATES PATENT OFFICE.

WILLIAM R. UHLEMANN, OF CHICAGO, ILLINOIS.

EYEGLASS-MOUNTING.

970,579.

Specification of Letters Patent. Patented Sept. 20, 1910.

Application filed April 4, 1910. Serial No. 553,327.

To all whom it may concern:

Be it known that I, WILLIAM R. UHLEMANN, a citizen of the United States of America, and a resident of Chicago, in the county of Cook and State of Illinois, have invented certain new and useful Improvements in Eyeglass-Mountings, of which the following is a specification.

This invention relates to that class of eyeglass mountings in which the nose guards are carried on the inner ends of manually operated levers pivoted on the rigid bridge piece of the mounting. And the present improvement has for its object to provide a simple and efficient structural formation and combination of parts adapted to afford a very compact and durable connection of the guard levers to the bridge, and with which the operating springs for the guard levers are inclosed and protected and at the same time attached at their inner ends to the guard levers in a strong and simple manner, all as will hereinafter more fully appear.

In the accompanying drawings:—Figure 1, is a plan view of any eyeglass mounting embodying the present invention. Fig. 2, is a front elevation of the same. Fig. 3, is a detail perspective view of portions of the bridge, guard levers and the spring, in a separated condition. Fig. 4, is an enlarged detail central longitudinal sectional elevation of the pivotal connection between the bridge, guard lever and spring. Fig. 5, is a similar view of a modification.

Similar numerals of reference indicate like parts in the different views.

Referring to the drawings, 1 represents the rigid bridge, to the respective ends of which are attached the clips or straps 2, by which the rimless lenses 3 are engaged and held in proper position.

In the present improvement the respective end portions of the aforesaid rigid bridge are of a wide and flat form, and are bent upon themselves to form rectangular shaped loops 4, with the free ends 5 of each loop in right-angle relation to the main portion of the bridge and abutting against the same, to afford a very rigid and substantial construction of the loops. The lower horizontal member 6 of each loop aforesaid, carries a centrally arranged pivot pin or pintle 7, upon which the hereinafter described guard lever has pivotal movement. The upper

horizontal member 8 of said loop is formed with a socket recess on its under side adapted to receive the upper end of the aforesaid pin or pintle 7 to afford a support for such upper and free end of said pin.

9 are the guard levers pivoted on the pivot pins 7, and immediately beneath the upper horizontal member 8 of the above described loop 4. The forward ends of said levers carry the usual finger pieces 10, while their rear ends carry the usual guards 11 of any usual construction and connected to the rear ends of the levers in any ordinary manner. 12 are springs arranged within said loops 4 of the bridge, immediately beneath the guard carrying levers 9, and having operative engagement with said levers to yieldingly press the guard carrying ends of the same toward each other, so that the nose guards 11 will have proper holding engagement with the nose of the wearer.

In the present improvement the springs 12 will be of the particular form described and claimed in my former application for Letters Patent, Serial No. 486,485, filed March 29, 1909, and each spring will comprise a flat strip or ribbon of resilient material coiled in volute relation around a pivot pin 7, and with the outer end extending away from the coiled body portion of the spring and adapted to bear against the inner face of an adjacent clip or strap 2 of the mounting, preferably by means of a bearing loop 13 at the end of said extended portion, in that the same affords a ready and convenient means for increasing or decreasing the tension of the spring by a slight coiling or uncoiling of the said loop 13 in one direction or the other, as set forth in detail in my aforesaid application Serial No. 486,485.

In my prior construction set forth in the aforesaid application, the inner ends of the volute springs were connected to the guard levers by being formed integrally therewith, while in the present construction said springs are made as separate pieces and connected to the guard levers by a construction of parts as follows:—

14 are lugs formed on the extreme inner ends of the springs 12 and projecting laterally therefrom as shown. Said lugs are adapted for engagement in side recesses 15 formed in the pivot orifices 16 of the guard levers 9, and are held from accidental disengagement by swaging down the upper

ends of said lugs 14 into cavities 17 formed in the guard levers at sides of the recesses 15 aforesaid.

In the assemblage of the parts of the present construction, the loops 4 heretofore described, will have the partly unfolded form illustrated in Fig. 3, and with the free upper ends of the pivot pins 7 exposed, so that the springs 12 and levers 9 may be placed upon said pivot pins, after which the said loops are pressed down to the final position shown, to engage the upper ends of the pivot pins and to inclose the pivot portions of the levers as well as the main bodies of the springs, and afford a neat and compact appearance to said portions of the completed mounting.

In the modification shown in Fig. 5, the aforesaid loops 4, heretofore described as being above the bridge ends, are arranged below the same, to provide a construction having advantages in some particular forms of the mounting.

Having thus fully described my said invention what I claim as new and desire to secure by Letters Patent, is:—

1. The combination in an eyeglass mounting, of a rigid bridge, pivot pins at the respective ends of the bridge, lens attaching

clips at the ends of the bridge, guard levers journaled on said pivot pins, and operating springs of a flat ribbon form encircling said pivot pins and connected at their inner ends to said levers by lateral lugs engaging in side recesses of the pivot orifices of the levers, the outer ends of said springs having rearwardly extending portions adapted for bearing against the rear faces of the attaching clips, substantially as set forth.

2. The combination in an eyeglass mounting, of a rigid bridge, pivot pins at the respective ends of the bridge, lens attaching clips at the ends of the bridge, guard levers journaled on said pivot pins, and operating

springs of a flat ribbon form encircling said pivot pins and connected at their inner ends to said levers by lateral lugs engaging in side recesses of the pivot orifices of the levers, the outer ends of said springs having rearwardly extending portions ending in curved loops adapted for bearing against the rear faces of the attaching clips, substantially as set forth.

3. The combination in an eyeglass mounting of a rigid bridge formed with wide and flat ends that are bent upon themselves to form rectangular loops the free ends of which abut against the bridge, pivot pins arranged centrally in said loops, guard levers arranged in said loops and upon the pivot pins, and operating springs also arranged in said loops and engaging said levers and a fixed portion of the mounting, substantially as set forth.

4. The combination in an eyeglass mount-

ing, of a rigid bridge formed with wide and flat ends that are bent upon themselves to form rectangular loops the free end members of which abut against the bridge, pivot pins carried by horizontal members of the loops, the companion horizontal members of the loops being formed with recesses to receive the free ends of the pivot pins, guard levers arranged in said loops and upon the pivot pins, and operating springs also arranged in said loops and engaging said levers and a fixed portion of the mounting, substantially as set forth.

5. The combination in an eyeglass mounting, of a rigid bridge formed with wide and flat ends that are bent upon themselves to form rectangular loops the free ends of which abut against the bridge, pivot pins arranged centrally in said loops, guard levers arranged in said loops and upon the pivot pins, and operating springs of a flat ribbon form encircling said pivot pins and connected at their inner ends to said levers by lateral lugs engaging in side recesses of the pivot orifices of the levers, the outer ends of said springs having rearwardly extending portions adapted for bearing against the rear faces of the attaching clips, substantially as set forth.

6. The combination in an eyeglass mounting, of a rigid bridge formed with wide and flat ends that are bent upon themselves to form rectangular loops, the free ends of which abut against the bridge, pivot pins arranged centrally in said loops, guard levers arranged in said loops and upon the pivot pins, and operating springs of a flat ribbon form encircling said pivot pins and connected at their inner ends to said levers by lateral lugs engaging side recesses of the pivot orifices of the levers, the outer ends of said springs having rearwardly extending portions ending in curved loops adapted for bearing against the rear faces of the attaching clips, substantially as set forth.

7. The combination in an eyeglass mounting, of a rigid bridge formed with wide and flat ends that are bent upon themselves to form rectangular loops the free end members of which abut against the bridge, pivot pins carried by horizontal members of the loops, the companion horizontal members of the loops being formed with recesses to receive the free end of the pivot pins, guard levers arranged in said loops and upon the pivot pins, and operating springs of a flat ribbon form encircling said pivot pins and connected at their inner ends to said levers by lateral lugs engaging in side recesses of the pivot orifices of the levers, the outer ends of said springs having rearwardly extending portions adapted for bearing against the rear faces of the attaching clips, substantially as set forth.

8. The combination in an eyeglass mount-

ing, of a rigid bridge formed with wide and flat ends that are bent upon themselves to form rectangular loops the free end members of which abut against the bridge, pivot pins carried by horizontal members of the loops, the companion horizontal members of the loops being formed with recesses to receive the free ends of the pivot pins, guard levers arranged in said loops and upon the pivot pins, and operating springs of a flat ribbon form encircling said pivot pins and connected at their inner ends to said levers by

lateral lugs engaging in side recesses of the pivot orifices of the levers, the outer ends of said springs having rearwardly extending portions ending in curved loops adapted for bearing against the rear faces of the attaching clips, substantially as set forth.

Signed at Chicago, Illinois, this 1st day of April 1910.
